FIG.1.

FIG.2.

FIG. 4.

FIG. 3.

FIG. 5.

FIG. 1 is a top plan view of an electric fuse for elevated voltages embodying our new design;

FIG. 2 is a side elevational view thereof;

FIG. 3 is a left end elevational view thereof;

FIG. 4 is a right end elevational view thereof; and

FIG. 5 is a developmental plan view of the decorative bands to an enlarged scale.

The conventional lining and solid black shading shown on the decorative bands in the drawing is to indicate contrast.

The broken lines in the drawing are for illustrative purposes only.

We claim:

The ornamental design for an electric fuse for elevated voltages, as shown and described.
